ANTENNA SYSTEM

Alan Julian Maddock, London W. C. 2, England,
assignor to Standard Telephones and Cables
Limited, London, England, a British company

Application March 10, 1943, Serial No. 478,683
In Great Britain March 27, 1942

5 Claims. (Cl. 250—11)

In radio antenna systems which have directive properties it is often desirable and in many cases necessary that the antenna system should emit radiation of one characteristic polarisation only whilst radiation of any other polarisation should be suppressed, e. g. in a system employing vertical antennae it is desirable that only waves of vertical polarisation should be emitted whilst all horizontal polarisation be suppressed and vice versa.

Polarisation of opposite characteristic can arise from currents induced in objects such as screens, towers, etc. which may be present and which can radiate in the unwanted mode. As an example, a directive antenna system consisting of vertical elements placed above the horizontal screened roof of a building or vehicle will radiate mainly waves of vertical polarisation but due partly to the limitation in size of such roof or screen and partly to the different potentials assumed by the various antennae elements near to said surface, currents will flow in the surface and may give rise to radiation which is horizontally polarised. Similarly an array of horizontal elements supported by structures such as metal poles or towers will radiate principally waves of horizontal polarisation but currents will be set up in the vertical members which may then radiate in the vertical mode. A single vertical antenna if located with one end in proximity to a conductor or sheet of limited dimensions can also give rise to horizontal polarisation due to the concentration of the current in the sheet more in one direction than in others.

In many applications it is necessary to suppress these unwanted radiations and a particular example of a system in which it is essential that this should be done is that in which two or more vertical elements are used to radiate electromagnetic waves which have intersecting polar diagrams in a horizontal plane and in which radiation is modulated in some rhythmic sequence between the two patterns, for example in the form of dots and dashes, so that an aircraft, fitted with suitable receiving apparatus—which includes a vertical receiving antenna—receives dots or dashes according to which side of the intersecting line it is located and along the line of intersection and for a small angle each side of which the dots and dashes merge into a continuous signal so giving an approach line for the aircraft along which it can be guided. Such systems are well known and in the past have usually taken the form of half-wave vertical elements supported at least a half wavelength above the earth and connected to the transmitter by suitable transmission line or lines.

It is often desired, however, that the antennae be placed on the top of a building or vehicle which latter contains the transmitter below the an-

tenna system, the roof of said building or vehicle often being screened or covered with mesh for reasons well known to those experienced in the art. As explained above currents set up in the horizontal roof or screen will radiate horizontally polarised waves and it is usually the case that the polar patterns of the radiation emitted in this sense are not the same as those of the primary emission, in this case that due to the vertical antennae. It is apparent then that should the receiving antenna not be vertical, for example in the case of an aeroplane when it banks, then a component of horizontally polarised radiation will be received and it may be that the signal will be of different character, e. g. dots may be received due to the horizontal polarisation where dashes would be received due to the vertically polarised radiation. Similar remarks apply when the main radiation is horizontally polarised. It is the object of this invention to provide a means for eliminating the radiation of unwanted characteristic at least over a considerable solid angle where its effects would be most harmful and in most instances it is found that immunity can be obtained at all points if conditions are satisfied at the most crucial points.

According to the present invention, in an antenna system comprising one or more antennae which has or have one end thereof in close proximity to a conducting sheet or other conducting system from which radiation is emitted polarised in a different sense from the radiation emitted by the main antenna system, one or a plurality of conducting screens or sheets or plurality of conductors are so disposed relative to the first mentioned conducting sheet or system that shielding of the radiation from said first mentioned conducting sheet or system is obtained within a desired solid angle.

The invention will be better understood from the following description taken in conjunction with the accompanying drawing in which Figure 1 shows a dipole antenna system located above a conducting sheet. Figure 2 is a side view and Figure 3 is a plan view of an antenna system embodying the invention.

Fig. 1 of the accompanying drawing is a diagrammatic representation of two antennae XY and X' Y' which are symmetrical about the points O and O' and may for example be half-wave antennae. The method of feeding power to the antennae is not shown as it is immaterial to the invention and may be carried out in well-known ways such as centre feeding the antennae at the points O and O', or end feeding at the points Y and Y' or feeding one and exciting the other parasitically and so on. The antennae are considered located above the surface or conductor MN which, as stated hereinbefore may be the roof of a building, vehicle or part of the antenna supporting

structure. If the curved lines A, B are taken to represent the distribution of electric lines of force at a given instant in the two antennae then it can be seen that since a certain number of lines of force from the bottom ends of the antennae terminate on the conductor MN a difference of potential will exist between the points M and N and a current I will flow in this conductor as shown by the arrow.

Fig. 2 is a view end-on to the antenna system of Fig. 1 and the current in the sheet MN flows perpendicularly to the paper at N. This current gives rise to radiation principally in directions at right angles to itself, horizontally polarised. If the points in space in which we are mainly interested in the radiation from the vertical antennae be perpendicular to the plane of the antennae then it is possible to eliminate the unwanted radiation at least within a certain solid angle; this may be sufficient for certain purposes where, for example, we are only concerned with receiving the vertically polarised radiation within certain limits of angle. For example, if an aeroplane is being guided by means of the radiation from the vertical antennae along a line perpendicular to the plane containing them, only radiation within an angle RNP is effective since even with an altitude of 10,000 feet at 10 miles distance, this angle is only 11° . Thus if we can eliminate the horizontal polarisation within this angle the system will be satisfactory.

The invention consists in placing a conducting sheet or screen PQ of such a size and in such a position relative to the position of the sheet or conductor MN that screening of the surface in which the unwanted current is flowing takes place over a certain angle PNQ in the vertical direction and the angle XSX' in the horizontal direction (Fig. 3). Thus within the solid angle bounded by the lines subtended by the limits of the sheet or screen PQ at the horizontal axis of the unwanted current and the axis of the vertical antennae, horizontally polarised radiation will be materially or completely reduced. Improvement in the reduction of the unwanted radiation can often be effected by the use of a plurality of sheets or screens and as an example a second screen is shown at P' Q'. By this means currents induced in the screen MN can be made to have a much smaller effect within the said solid angle since radiation set up by such currents is reflected back by the screen or screens PQ.

It is also possible to reduce the radiation in the opposite direction NR' by adjustment of the spacing NR such that the currents set up in the screen PQ by the current in MN in conjunction with the distance NR can be made to be in opposite phase and thus cancel, at least in part, as far as radiation is concerned in this general direction. It is not usually possible to effect a complete elimination of reduction in direction NR' in this way since the current in PQ will generally be smaller in magnitude than that in MN so that although phase reversal can be effected complete cancellation will be absent due to inequality of the currents. A greater current can however be induced in the screen PQ by making the length such that it is resonant or nearly so at the operating frequency when more exact cancellation can be obtained.

In the case considered of the half-wave anten-

nae, the loss of forward field strength of the vertical radiation is negligible since the portions of the antennae in the region of the current loops, O, O' are unshielded. With quarter wave antennae, 5 however, where the conductor MN forms part of the counterpoise for the radiating elements and where the current loop occurs at the base of the antennae some loss of field strength may occur but cancellation of the horizontal polarisation 10 can again be effected in the manner already indicated.

It will be observed that the invention is equally applicable to horizontal antennae when correction must be applied to eliminate vertical polarisation. 15 In this case XY and X' Y' are horizontal radiating elements and PQ and MN vertical members. Furthermore, extension to inclined antennae will also be understood to those skilled in the art.

20 Whilst the foregoing description deals with half-wave and quarter-wave antennae the invention is equally applicable to antennae of any length.

The invention may also be applied to cases in 25 which correction is required for all directions about the central axis of the antenna system. Then screening sheets of conductors may be placed all round the conductor MN so that shielding is effective in all or any desired direction.

30 What is claimed is:

1. An antenna system comprising an antenna having a polarized radiation characteristic and a conducting surface arranged in close proximity to one end of said antenna and having a radiation characteristic polarized along an axis of polarization different from that of the radiation characteristic of said antenna, and conducting means extending across a predetermined solid angle formed around said axis of polarization for 35 shielding said antenna from the radiation polarized along said axis of polarization.

2. An antenna system as claimed in claim 1, in which the conducting means is a screen intersecting the conducting surface.

40 3. An antenna system as claimed in claim 1, in which the conducting means comprises two conducting screens intersecting the conducting surface and placed one behind the other.

45 4. An antenna system as claimed in claim 1, in which the conducting means comprises a screen having a radiation characteristic polarized along an axis substantially parallel to that of the radiation characteristic of said antenna and intersecting the conducting surface at a distance such that currents set up in said screen by said antenna and by the current in said conducting surface are substantially opposite in phase.

50 5. An antenna system as claimed in claim 1, in which the conducting means comprises a screen substantially resonant at the operating frequency of the antenna and having a radiation characteristic polarized along an axis substantially parallel to that of the radiation characteristic of said antenna, said screen being arranged intersecting the conducting surface at a distance from the antenna such that currents set up in said screen by said antenna and by the current in said conducting surface are substantially opposite in phase, to reduce radiation in a direction opposite 55 to said solid angle.
